(57) **CLAIM**

The ornamental design for a handbag, as shown and described.

DESCRIPTION

1. Handbag

1.1 : Perspective

1.2 : Front

1.3 : Back

1.4 : Right

1.5 : Left

1.6 : Top

1.7 : Bottom

1.8 : Open perspective

The bag consists of an essentially rectangular body with two side gussets and a flap covering the upper and middle parts of the front side of the body; a horizontal semi-circular retaining element is attached to the latter; one end of a chain that extends over the top of the body and in front of the flap is connected to the rear side of the body; the other end of the chain has a small rod that can be inserted through the aforementioned retaining element when the bag is closed; the links of the chain are almost elliptical in shape and have a small intermediate transverse bar, resembling anchor chains.
